UNITED STATES PATENT OFFICE

CURTIS L. HOWSE, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed January 14, 1924, Serial No. 686,183. Renewed July 20, 1931.

The invention relates to boiler cleaners particularly of that type having a blower element through which cleaning fluid such as steam or the like is discharged to clean the boiler tubes or other parts of the boiler.

The invention has among its objects the provision of an improved boiler cleaner of the type mentioned.

With this as well as other objects the invention further resides in the novel features of construction and combinations and arrangements of parts as more fully herein-after set forth.

In the drawings:

Figure 1 is an end view of a blower element embodying my invention;

Figure 2 is a cross section on the line 2—2 of Figure 1;

Figure 3 is a view similar to Figure 2 showing a modified construction;

Figure 4 is a cross section on the line 4—4 of Figure 3.

1 is a rotary blower element provided with nozzles through which the cleaning fluid such as steam or the like is discharged upon the boiler tubes or other parts of the boiler. 2 is an axially aligned valve adapted to engage the seat 3 near the inner end of the blower element. 4 is the valve body in which the sleeve 5 is journalled, this sleeve being rigidly secured to the blower element 1 and the seat 3 which are threaded thereinto. The sleeve has the ports 6 which communicate with the passageway 7 in the valve body constituting the inlet for the cleaning fluid.

8 is the valve stem extending in axial alignment with the blower element and having the threaded portion 9 engaging the gear 10. This gear meshes with the planetary gears 11 which are journalled upon the stub shafts 12 and mesh with the internal gear 13 rigidly secured upon the valve body 4. The stub shafts are secured to the ring 14 which is threaded upon and rigidly secured to the sleeve 5 beyond the valve body. 15 is a stop in the form of a collar secured upon the valve stem 8 and engageable with the gear 10 upon rotation of the valve stem relative to the gear to secure an outward longitudinal movement of the valve stem. This gear 10 is held from

longitudinal or axial movement by means of the plate 16 upon the stub shafts 12 and having portions engaging in grooves 17 in the hub of the gear. 18 is a sheave wheel rigidly secured upon the valve stem beyond the gear 10 and adapted to be rotated by suitable means such as a chain.

For the purpose of assuring the opening of the valve 2 prior to the rotation of the blower element 1 and preventing closing of the valve before the blower element has rotated through its complete blowing arc, I provide the piston 19 which is secured upon the valve stem and slidably engages the sleeve 5, this piston having piston rings 20 at its ends and an annular intermediate grooved portion 21. The piston is located even when the valve is closed beyond the ports 6 in the sleeve, and as a consequence this piston is subjected to the pressure of the cleaning fluid at all times which tends to longitudinally move the piston outward and open the valve.

To limit the angular travel of the blower element, the ring 14 has the stop member 22 in the form of an outwardly extending lug and the valve body has the stop member 23 in the form of an inwardly extending projection upon the internal gear 13. This inwardly extending projection is preferably a detachable member such as a cap bolt which is threadedly engageable with the internal gear at different points in its periphery to vary the angular travel of the blower element.

In operation and with the valve in closed position as shown in Figure 2, rotation of the sheave wheel 18 in a clockwise direction by means of the chain will first rotate the valve stem 8 relative to the gear 10 thereby longitudinally moving the valve stem outwardly and opening the valve 2. This motion takes place in preference to the rotation of the gear 10 owing to the difference in pressures exerted by the cleaning fluid and acting upon the piston 19 and valve 2, which tends to move the valve stem longitudinally outward. The relative rotation of the valve stem 8 and gear 10 continues until the stop 15 comes into contact with the gear 10, after

which the gear 10 is rotated with the valve stem and through the planetary gears 11, internal gear 13, ring 14 and sleeve 5 rotates the blower element. This rotation continues until the stop member 22 upon the ring 14 comes into contact with the stop member 23 upon the internal gear. Then upon reversing the rotation of the sheave wheel 18, the blower element is rotated in the reverse direction through the same arc until the stop member 22 comes into contact with the stop member 23 which again limits the rotation of the blower element after which continued rotation of the sheave wheel in the same direction compels a relative rotation of the valve stem 8 and gear 10 and consequent longitudinal inward movement of the valve stem against the differential pressure exerted by the cleaning fluid, thereby seating the valve 2 and shutting off the passage of the cleaning fluid through the blower element.

In the event of any leakage of the cleaning fluid past the piston ring in the inner end of the piston 19, this cleaning fluid is conducted to the boiler by means of the leak-off passageway 24 in the valve body. As illustrated in Figure 2 of the drawings, this passage opens at its inner end into the annular space between the blower element and the wall box 23' which extends through the boiler setting 24'.

As shown in the modified construction, Figures 3 and 4, 25 is the rotary blower element having its end secured in the sleeve 26 and 27 is the valve in axial alignment with the blower element. This valve has portions at its opposite ends adapted to engage the seats 28 and 29 secured in the sleeve 26, the valve being so located that when seated the portion thereof intermediate the seats comes into contact with the cleaning fluid entering the inlet passage 30 in the valve body 31.

32 is the valve stem secured to the valve and having the threaded portion 33 intermediate its ends engaging in the gear 34 which latter is located beyond the end of the sleeve 26. This gear meshes with the gear 35 mounted upon the stub shaft 36 secured to the valve body. 37 is a pinion also mounted upon the stub shaft 36 and driven from the gear 35, and 38 is another gear meshing with the pinion 37 and secured upon the sleeve 26 for rotating the same and consequently the blower element 25. The gear 34 is journaled in the bracket 39 secured to the valve body 31 and is held from moving axially outward relative to the bracket by means of the anti-friction thrust bearing 40 which, in the present instance, is a ball bearing. The valve stem 32 is rotated by means of the sheave wheel 41 engaged by a suitable flexible connection such as a chain and this valve stem is also provided with a piston 42 which, as soon

as the valve is partly opened is acted upon by the cleaning fluid thereby tending to force the valve stem longitudinally outward to fully open the valve. Furthermore, the valve stem is provided with the stop 43 between the gear 34 and the piston 42 and engageable with the gear to limit the rotation of the valve stem relative to the gear.

For limiting the angular travel of the blower element 25, I have provided the transverse projection or stop 44 upon the gear 38 and also the projection 45 upon the bracket 39 and engageable with the stop 44. To secure the rotation of the blower element through an arc equal to or greater than 360°, the gear 38 is provided with a concentric slot 46 in which the stop 44 is slidable, the degree of angular travel of the blower element depending upon the length of this slot.

The operation of this boiler element is the same as that disclosed in Figures 1 and 2, the main difference being the provision of a balanced valve and the provision of means for providing for the rotation of the blower element through an arc equal to or greater than 360°.

In this application no claims are directed to the means provided for conducting the leaking cleaning fluid to the interior of the boiler setting, since this feature is described and claimed in a copending application filed February 15, 1924, Serial No. 693,609, in which application I am a joint applicant with Norman L. Snow.

What I claim as my invention is:—

1. In a boiler cleaner, the combination with a rotary blower element, a valve seat carried by said element and a valve co-operating with said valve seat for controlling the passage of cleaning fluid to said blower element, said valve being movable longitudinally of said blower element, of a rotatable driving member, a stem for said valve fixed to said rotatable driving member for rotation therewith and means for operating said valve during a portion of the rotation of said driving member and for operating said blower element during another portion of rotation.

2. In a boiler cleaner, the combination with a rotary blower element, and an axially aligned valve for controlling the passage of cleaning fluid through said blower element, of a valve stem for said valve having a threaded portion, a gear upon the threaded portion of said valve stem and operatively connected to said blower element, means for rotating said valve stem, and means providing for the rotation of said valve stem relative to said gear and consequent longitudinal movement of said valve stem and also providing for the rotation of said gear with said valve stem.

3. In a boiler cleaner, the combination with a rotary blower element, and an axially aligned valve for controlling the passage of cleaning fluid therethrough, of a valve stem

- for said valve having a threaded portion, a gear upon the threaded portion of said valve stem and operatively connected to said blower element, means for rotating said valve stem, a piston operated upon by the cleaning fluid and tending to move said valve stem longitudinally outward to open said valve, and a stop upon said valve stem engageable with said gear for limiting the longitudinal outward movement of said valve stem. 5
4. In a boiler cleaner, the combination with a rotary blower element, and a valve for controlling the passage of cleaning fluid through said blower element, of a rotatable member connected to said valve, a second rotatable member, gearing operatively connecting said second rotatable member to said blower element, and means upon said rotatable members for moving said first-mentioned rotatable member longitudinally to open and close said valve and means coacting with said last mentioned means for rotating both rotatable members together. 15
5. In a boiler cleaner, the combination with a rotary blower element, and a valve for controlling the passage of cleaning fluid through said blower element, of a valve stem for said valve, means for rotating said valve stem, gearing for rotating said blower element including a gear threaded upon said valve stem, and a stop upon said valve stem and engageable with said gear to limit the longitudinal movement of said valve. 25
6. In a boiler cleaner, the combination with a rotary blower element, and a valve for controlling the passage of cleaning fluid therethrough, of a rotatable member connected to said valve, a second rotatable member operatively connected to said blower element, means upon said rotatable members for moving said first-mentioned rotatable member longitudinally to open and close said valve and means coacting with said last mentioned means for locking said rotatable members 40 against movement with respect to each other whereby said rotatable members rotate together, and means for variably limiting the rotation of said second rotatable member. 45
7. In a boiler cleaner, the combination with a rotary blower element, and a valve for controlling the passage of cleaning fluid therethrough, of a valve stem, means for rotating said valve stem, and means providing for the operation of said valve and blower element including planetary gearing having a gear threaded upon said valve stem. 55
8. In a boiler cleaner, the combination with a rotary blower element, and an axially aligned valve for controlling the passage of cleaning fluid therethrough, of a valve stem for said valve having a threaded portion, a gear upon the threaded portion of said valve stem and operatively connected to said blower element, means for rotating said valve stem, means operable to urge said valve stem longitudinally outward to open said valve, and a stop upon said valve stem engageable with said gear for limiting the longitudinal outward movement of said valve stem. 60
9. In a boiler cleaner, the combination with a rotary blower element, and a valve for controlling the passage of cleaning fluid therethrough, of a valve stem, means for rotating said valve stem, and means providing for the operation of said valve and blower element, said last mentioned means including planetary gearing having a gear through which said valve stem is longitudinally movable and means for limiting longitudinal movement of said valve stem through said gear. 65
10. In a boiler cleaner, a rotatable blower element, valve means for controlling the flow of cleaning fluid to said blower element including a valve seat member coaxial with said blower element and rotatable therewith and a valve member engageable with said seat member, a gear on said rotatable blower element for rotating the same, a pinion engageable with said gear, and means for rotatably driving said pinion to rotate said blower element, said means being also operable to effect a relative movement between said valve member and said valve seat member to admit cleaning fluid to said blower element. 70
11. In a boiler cleaner, a rotatable blower element, a rotatable drive member, means including planetary gearing driven by said drive member for rotating said blower element, a valve for controlling the flow of cleaning fluid to said blower element, and a connection between said drive member and valve for actuating the valve upon actuation of said drive member. 75
12. In a boiler cleaner, a rotatable blower element, a valve controlling the flow of cleaning fluid to said blower element, a stem for said valve, a member operatively connected to said blower element and threaded on said stem, and means operable to rotate said stem relative to said member to actuate said valve, said means being also operable to rotate said stem with said member to rotatably drive said blower element. 80
- In testimony whereof I affix my signature. 85
